UNITED STATES PATENT OFFICE.

HEZEKIAH G. UFFORD, OF BOSTON, MASSACHUSETTS.

ADJUSTABLE FORM FOR GARMENTS.

SPECIFICATION forming part of Letters Patent No. 233,173, dated October 12, 1880.

Application filed June 19, 1880. (No model.)

To all whom it may concern:

Be it known that I, HEZEKIAH G. UFFORD, of Boston, in the county of Suffolk and State of Massachusetts, have invented certain new and useful Improvements in Adjustable Forms for Ladies' Garments, of which the following is a specification.

The object of my invention is to provide a cheap, simple, and convenient adjustable form for exhibiting ladies' dresses and other garments in such a manner that a single form may be so adjusted, expanded, or contracted throughout its entire length from top to bottom as to fit within any desired size of a lady's dress, so as to show the style of drapery, the flow of the skirts, and the size, style, cut, and make of the waist of the same as readily as if it were placed upon a human being; and it consists in the construction, combination, and arrangement of the parts forming the wire skeleton-frame, as hereinafter more fully described and set forth.

Figure 1 is a perspective view of a frame constructed according to my invention. Fig. 2 is a similar view of the interior standard and adjusting parts removed.

A represents the base of the frame, into which is secured the vertical tube B, having a set-screw, C, near its upper end, so as to retain the adjustable vertical rod or upright support D in an elevated position, as may be desired. Fitted upon this support D is a short vertical tube, E, having right-angled or horizontal tubes F F', provided with set-screws G G', so as to retain the side support-rods, H H', the lower ends of which are bent at right angles so as to fit within the outer ends of the horizontal tubes F, so as to allow of horizontal adjustment of the wire skeleton-forms L L', to which the upper ends of the support-rods H H' are secured, as shown.

It will be seen that these wire skeleton-forms

L L' are completely separated from top to bottom, or vertically, forming right and left halves, L L', and are provided at their top or neck 45 portions, II', with horizontal adjusting loops or slots J J', and are held in the desired position horizontally by means of the thumb-nut or screw-knob K, which fits a screw-thread upon the upper end of the vertical support-rod D, 50 over which the loops or slots J of the skeleton-frame L L' are passed, the bottom or lower portion of said wire skeleton-form frames being provided with similar adjusting loops or slots P P', and a set-screw, T, and slides R R. 55 These bottom loops or slots, P P', pass or slide horizontally upon the vertical tube B, as shown.

Thus it will be seen that the skeleton-form composed of the two wire frames L L' is adjustable horizontally, so as to permit the diameter of the form to be enlarged or reduced at pleasure, and secured at such size against movement temporarily at either the neck or bust, waist, or bottom skirt portion, and that the whole may be lowered or raised as occasion may require, or revolved about the central support or standard, which diametrical adjustment is a distinguishing and essential feature of my invention.

Having thus described my invention, what I claim is—

In combination with the adjustable standard B D, the adjustable skeleton-frames L L' divided longitudinally from top to bottom, and provided with the adjusting-loops J J' P P', 75 the screw-knob K, and having the tubes E F F', support-rods H H', set-screws G G', and slides R R, provided with the set-screw T, all being constructed substantially as shown and described, as and for the purposes set forth. 80

HEZEKIAH G. UFFORD.
